UNITED STATES PATENT OFFICE.

HENRY J. GILBERT, OF SAGINAW, MICHIGAN.

DESIGN FOR A SOAP-REST FOR WASHBOARDS.

52,236.

Specification for Design.

Patented July 30, 1918.

Application filed January 15, 1916. Serial No. 72,351. Term of patent 14 years.

To all whom it may concern:

Be it known that I, HENRY J. GILBERT, a citizen of the United States, residing at Saginaw, in the county of Saginaw and State of Michigan, have invented a certain new, original, and ornamental Design for Soap-Rests for Washboards, shown in the accompanying drawing, in which the soap-rest embodying my novel design is shown in solid lines and the outline of the wash-board in which the soap-rest is employed is indicated in dotted lines.

I claim:

The novel design for a soap-rest for washboards illustrated in the accompanying drawing.

HENRY J. GILBERT.
